Primary Examiner — Darlington Ly

(57) **CLAIM**

The ornamental design for a flower vase, as shown and described.

DESCRIPTION

1. Flower vase
1.1 is a front perspective view of a flower vase embodying my new design;
1.2 is a left side perspective view thereof;
1.3 is a top, front, and left side perspective view thereof;
1.4 is a top perspective view thereof;
1.5 is a bottom plan view thereof;
1.6 is a partial and enlargement front elevation view thereof, in which the area of enlargement is taken at the center; and
1.7 is a partial and enlargement front elevation view thereof, in which the area of enlargement is taken at the base.
